UNITED STATES PATENT OFFICE

SAMUEL E. FEGLY, OF LANCASTER, PENNSYLVANIA

OIL BURNER

Application filed February 3, 1927. Serial No. 165,613.

This invention relates to oil burners and has special reference to an improved oil burner arranged to produce a fine mist of oil through the proper intermixing of oil and 5 air.

One important object of the invention is to provide an improved means of producing an initial nebulizing of the inflowing oil.

A second important object of the invention 10 is to provide improved means for regulating the initial nebulizing effect.

A third important object of the invention is to provide an improved burner wherein 15 the primary and secondary nebulization of the oil will be effected, the secondary nebulizing means further reducing the size of the already minute globules of oil produced by the primary nebulizing means by breaking these globules into fractional portions.

20 A fourth important object of the invention is to provide means for maintaining the oil as secondarily nebulized in the high state of nebulization produced by the secondary nebulizer.

25 With the above and other objects in view as will be hereinafter apparent, the invention consists in general of certain novel details of construction and combinations of parts hereinafter fully described, illustrated 30 in the accompanying drawings and specifically claimed.

In the accompanying drawings like characters of reference indicate like parts in the several views, and:

35 Figure 1 is a longitudinal diametric section through a burner constructed in accordance with this invention.

40 Figure 2 is an enlarged longitudinal section of the forward portion of the main part of the body showing the primary nebulizer arrangement.

Figure 3 is a section on the line 3—3 of Figure 1.

45 Figure 4 is a section on the line 4—4 of Figure 1.

Figure 5 is a section on the line 5—5 of Figure 1.

50 Figure 6 is a view of a certain ported dia-

Figure 7 is a section on the line 7—7 of Figure 6.

Figure 8 is a section on the line 8—8 of Figure 6.

Figure 9 is a face view of one form of a jet 55 disk used herewith.

Figure 10 is a section on the line 10—10 of Figure 9.

Figures 11 and 12 are face views of modified forms of the jet disks. 60

While the invention is capable of many and various embodiments but one is shown in the present drawings wherein it will be seen that the burner is provided with a body 10 wherein is a main bore 11 terminating 65 forwardly in a reduced portion 12 having its front end closed except for an outlet port 13 so that this end forms a valve seat. The body is provided with a lateral air inlet port 14 so that an air pipe 15 may be connected 70 to the body and air delivered in the bore 11.

The rear end of the bore is threaded and to the rear of the threaded portion is provided a stuffing box 16 having a packing gland 17. Extending through the stuffing box is an oil 75 supply tube 18 having a threaded portion 19 engaging the threads of the bore so that rotation of this tube will cause longitudinal movement in the body, a handle 20 being provided to effect this rotative movement. The 80 forward end of this tube is closed by a tip 21 having a plurality of rearwardly inclined ports 22 which open into the space surrounding the tube and either into the smaller front portion of the bore or behind the abrupt 85 shoulder 23 into the larger portion of the bore according to the position given the oil supply tube. Thus the flow of oil may be retarded or allowed freedom of passage.

This part of the device forms a primary 90 nebulizer, the air stream flowing forwardly meeting the fine oil jets issuing from the ports 22 in a rearwardly inclined direction and breaking the oil up into a mist so that the nebulized oil may flow out of the port 95 13. Moreover the front end of the tip 22 forms a valve which cooperates with the valve seat before mentioned to regulate the flow of nebulized oil and air through the port 13. 100

Screwed into the front end of the body and forming a forward extension thereof is a nozzle 24 wherein is held a multiple armed spider 26 supporting a short axially extending shaft 28. On this shaft is mounted a nebulizing wheel 27 having a series of ports 28' therein and carrying inclined blade portions 29 extending over these ports on the front face of the wheel. Thus the primarily 5 nebulized oil passes through the spider and ports 28' and, striking the blades 29, causes rapid rotation of the secondary nebulizing wheel and thus breaks up the already small globules of oil into exceedingly minute fractions.

15 Forward of the wheel 27 and spaced therefrom is a diaphragm 30 having ports 31 inclined as shown to produce a swirling action on the nebulized oil and air flowing therethrough and thus preventing segregation 20 of the oil in the forward part of the chamber.

25 The forward end of the chamber is closed by a jet disk 32 having one or more ports 33 of any desired shape or arrangement therein and these ports may either lead straight through the disk as in Figure 1 or may be shaped to guide the mixture of oil and air at an angle to the burner as shown in Figures 9 and 10. This disk rests on a 30 gasket 34 supported on the front edges of the nozzle and held thereon by a clamping ring 35, the disk being provided with positioning pins 36 so that it may be adjusted to bring the port or ports 33 into desired 35 position.

There has thus been provided a simple and efficient device of the kind described and for the purpose specified.

It is obvious that minor changes may be 40 made in the form and construction of the invention without departing from the material spirit thereof. It is not, therefore, desired to confine the invention to the exact form herein shown and described, but it is desired 45 to include all such as properly come within the scope claimed.

Having thus described the invention, what is claimed as new, is:

1. In an oil burner, a body having a bore 50 therein provided with an air inlet and having an outlet end, an oil supply tube arranged axially of the bore and having its forward end closed and forming a valve, said oil supply tube having a plurality of ports opening 55 laterally through its side wall and located in advance of the air inlet, said outlet end of the body forming a valve seat, for said valve, said body having at its forward end an enlarged chamber, a multiple spoked 60 spider fixed transversely of the said chamber, a nebulizing wheel revolvably associated with said spider, said nebulizing wheel having a plurality of ports and being provided with deflector blades on its forward face 65 projecting over said wheel ports, and a

ported jet disk closing the forward end of said chamber.

2. In an oil burner, a body having a bore 70 therein provided with an air inlet and having an outlet end closed and forming a valve, said oil supply tube having a plurality of ports opening laterally through its side wall and located in advance of the air inlet, said outlet end of the body forming a valve seat, for said valve, said body having at its forward end an enlarged chamber, a multiple spoked spider fixed transversely of the said chamber, a nebulizing wheel revolvably associated with said spider, said nebulizing 75 wheel having a plurality of ports and being provided with deflector blades on its forward face 80 projecting over said wheel ports, a ported jet disk closing the forward end of said chamber, and a diaphragm fixed between the nebulizer wheel and the jet disk and provided with a plurality of ports spaced from the center of the diaphragm and inclined to produce a swirling action of the nebulized oil in the space between the diaphragm and jet disk.

3. In an oil burner, a body having a bore 85 therein provided with an air inlet and having an outlet end, said body having at its forward end an enlarged chamber, a multiple spoked spider fixed transversely of the said chamber, a nebulizing wheel revolvably associated with said spider, said nebulizing wheel having a plurality of ports and being provided with deflector blades on its forward 90 face projecting over said ports, a ported jet disk closing the forward end of said chamber, and a diaphragm fixed between the nebulizer wheel and the jet disk and provided with a plurality of ports spaced from the center of the diaphragm and inclined to produce a swirling action of the nebulized oil in the space between the diaphragm and jet disk.

In testimony whereof I affix my signature. 100
